APPARATUS FOR HOLDING AN ANCHOR
IN A MOLD

George J. Saffert, New Ulm, Minn.

Application August 8, 1941, Serial No. 406,020

2 Claims. (Cl. 25—118)

My invention relates to an improvement in concrete slab anchoring device, and method of embedding the same, where it is desired to provide an effective anchor for holding the slabs in position as a wall facing.

Cast stone or concrete slabs are often used for facing concrete and masonry walls of building structures. When the slabs are used as a facing for a concrete wall, an inner concrete form wall of any usual type is erected; and the slabs are secured in spaced parallel relation thereto to provide the outer form wall. The slabs are held in place by anchors which extend into the slabs, connecting the slabs to the inner form wall. Concrete is poured between the inner form wall and the slabs, embedding the anchors. Thus, when the concrete has set, the anchors are embedded both in the slabs and the wall body, firmly connecting the slabs and the concrete wall together.

Certain difficulties have arisen in the use of anchors connecting the slabs to the wall. The slabs are subjected to greater, or quicker, changes of temperature than is the concrete wall. In the past, the slab anchors have sometimes been in the form of wire loops or metal strips which are embedded in the slabs and project therefrom. These wire loops or strips extend directly from the surface of the slabs into the concrete wall. Upon expansion and contraction of the slabs, relative movement between the wall and the slabs, tending to weaken the anchor or to injure the slabs adjacent the anchor.

In order to permit limited movement between the slabs and the concrete wall, attempts have been made to place a resilient tube around the anchor strip or loop adjacent the slabs and extending into the wall body a short distance. Such resilient tubes permit slight relative movement between the slabs and the concrete wall body, the anchoring loops or strips flexing the resilient tubes to some extent. Such a construction is slow, costly, and somewhat uncertain. The resilient tubes form a weak spot in the wall adjacent the anchors, tending to secure the anchor less effectively.

An object of the present invention lies in the provision of a means of permitting limited movement between the slabs and the wall. An anchoring bolt or strip may be anchored firmly and permanently embedded in the wall body and project therefrom into engagement with the anchor embedded in the slab. Relative movement is permitted between the bolt or strip and the slab anchor, thus compensating for the necessary differences in expansion and contraction.

When the slabs are used as a facing for masonry walls or other types of walls, less difficulty is experienced with expansion and contraction; but it is still extremely desirable to provide an anchor which is embedded within the slab and which does not project from the surface thereof. Obviously, when the embedded anchor protrudes from the body of the slab, the slabs cannot be piled one upon the other, and must be held in spaced relation. The cost of shipping the slabs is accordingly increased when embedded anchors of the old type are employed. When the anchors do not protrude from the slab body, however, the slabs may be piled one upon the other without injury to the slabs or anchors.

A feature of the present invention lies in the manner of embedding the anchor within the slab. The anchor is preferably in the shape of a substantially U-shaped strip or rod provided with outwardly projecting end flanges. The closed end of the U-shaped strip or rod is designed to extend substantially flush with the rear surface of the slab, the sides of the U, and the end flanges thereupon, extending into the body of the slab. A pocket or recess is provided in the rear surface of the slab, between the sides of the U-shaped bracket or anchor, so that the closed end of the anchor bridges the pocket. A bolt may extend through this bridge portion of the anchor if the anchor is formed of a flat strip; or a hook may encircle the bridge portion of the anchor if the anchor is formed of a rod. This bolt or hook is embedded or otherwise affixed to the wall, connecting the slabs to the wall.

These and other objects and novel features of my invention will be more clearly and fully set forth in the following specification and claims.

In the drawing forming a part of my specification:

Figure 1 is a perspective view of a small section of a concrete or cast stone slab illustrating the construction thereof.

Figure 2 is a rear elevation view of a section of the slab shown in Figure 1, illustrating the anchor construction.

Figure 3 is a perspective view of a portion of the mold showing the anchor and removable lugs in place thereupon before the casting of the slab.

Figure 4 is a sectional view through a portion of a concrete slab through the anchoring device and through the removable lugs illustrating in dotted outline the method of removing these lugs.

Figure 5 is a sectional view through a concrete form for casting concrete wall facings with cast

slabs, showing the facing being used as one side of the form.

Figure 6 is a perspective view of a small section of the slab similar to Figure 1, but showing a slightly different type of anchor.

Figure 7 is a perspective view through the slab in Figure 6 showing the pocket form, the lugs in position in the slab before removal thereof.

The slabs A may be formed of concrete or other suitable material and may be of any desired size to serve their purpose. These slabs are ordinarily several square feet in area and from one and one-half to three and one-half inches in thickness. Only a small section of the slab is illustrated in Figure 1, as it is this portion of the slab with which the present invention is concerned.

The slab A is provided with a decorative front surface 10 of any desired type and a rear surface 11. Embedded in the slab A, I provide a substantially U-shaped anchor B having opposed outwardly extending flanges 12 thereupon. The anchors B each include a central closing end 13, a pair of opposed sides 14 and outwardly extending flanges 12 projecting from the extremities of the sides 14. The central portion 13 is designed to lie substantially flush with the rear surface 11 of the slab A, while the sides 14 and flanges 15 extend into the body of the slab and are anchored in place thereby.

An elongated pocket or aperture 15 is provided which extends at substantially right angles to the anchor B between the sides 14 thereof. This recess or pocket 15 includes a pair of downwardly and inwardly extending side walls 16 which are connected by a curved or arcuated surface 17. Thus the central portion 13 of the anchors B bridge the pockets 15 and permit access to the rear side of the center portion 13 of the anchors. A central aperture 19 is provided in the center portion 13 of the anchor B, the purpose of which will be later described in detail.

In the formation of the pocket 15 and in embedding the anchor B in place, I employ the arrangement illustrated in Figure 3 of the drawing. In this construction I illustrate a form lug made up of a pair of lugs 20 arranged in abutting relationship to form a recess 15. When the slabs are cast with the outer surfaces uppermost in the mold these lugs 20 are secured to the lower surface of the mold 21 in the manner illustrated in Figure 3 of the drawing. The lugs 20 are held in this position by brads or small nails 22 which extend in slots 23 in opposed ends of the lugs 20. Each of the lugs 20 comprises a flat surface 24, which is designed to rest upon the mold 21 during the formation of the slab, a pair of side walls 25 forming opposite sides of the lugs, and a curved surface 26 which forms a base 17 of the aperture 15.

In order that the lugs 20 may hold the anchor B in place during formation of the slab, each lug 20 is provided with a notch 27 in the edge between the flat surface 24 and the abutting ends 29 of the lugs. These notches 27 engage the opposite sides of the center portion 13 of the anchor B and taper away from the anchor B toward the abutting edges 29 so as to render the lugs removable from the mold. The lugs and anchor are cast into the slab by pouring concrete about the same while in the position indicated in Figure 3, and when the concrete forming the slab has hardened the lugs 20 may be removed by tapping the same lightly with a hammer and pivoting the separate lugs out from beneath the central bridging portion 13 of the anchor B. In

Figure 4 of the drawing, I disclose the lugs 20 in position in the slab A, while in dotted outline in this figure I disclose the lugs partially removed. The lugs 20 are provided with a slightly rounded edge 30 at the juncture between the arcuated surface 26 and the abutting end 29 so as to simplify the removal of the lugs 20.

In Figure 5 of the drawing, I disclose the manner in which the anchors are used in the preparation of a concrete wall. The inner form wall 31 is erected in the usual manner and the outer form wall is made up of the slabs A, which are connected to the inner form wall in the manner illustrated. Anchor bolts 32 extend freely through the apertures 19 with sufficient play to permit relative movement between the bolt and the anchor lock nuts 33 are provided on the bolt 32 and are tightened sufficiently to hold the slabs in place, but are sufficiently loose to permit relative movement between the bolt 32 and the anchor B. The anchor bolt 32 extends into a substantially frustro-conical nut 34 which has its large diameter end abutting the form wall 31. The bolt 32 does not extend entirely through the nut 34 and a fastening bolt 35 is threaded into the nut from the large diameter end and extends through the form wall 31, being secured by means of a nut 36. Thus the slabs A are held in proper relationship to the inner form wall to form an outer form wall and to provide a form within which concrete may be poured.

The slabs A are preferably spaced by wedges or strips and the slab wall thus formed is roughly painted on the inside to prevent the concrete from leaking therethrough. The pockets or recesses 15 are then preferably filled with clay or some other inexpensive soft material which is readily obtainable. Mud or wet clay has been used with good effect for this purpose. When the aperture or pockets 15 are filled concrete is poured between the inner form wall 31 and the slabs A, the clay preventing the concrete from filling the pockets 15. When the concrete has set the wall is formed and it will be noted that while bolts 32 are firmly embedded in the concrete wall, they extend loosely through the anchor B and relative movement can take place between the slab and the wall without any deleterious effects. The bolts 35 may be removed and if desired the nuts 34 may be removed, leaving a conical aperture on the inner side of the concrete wall and a nut of the usual shape may be threaded upon the end of the anchor bolt 32.

In the foregoing description I have described the construction of the lugs when the slabs are cast with the exposed surface uppermost. In some instances, these slabs are cast with their exposed surface downwardly against the base of the mold. In such an instance, the lugs 20 may be secured to a strip of wood, or the like, and urged down into the concrete after it has been poured, thus becoming embedded in the rear surface of the slab, which is in such a case uppermost in the mold.

In Figures 6 and 7 of the drawing, I disclose a modified form of construction in which a slightly different form of anchor is employed. The anchor C is preferred where the slabs are used to face masonry walls or the like. These slabs C are preferably used in combination with a flat strip anchor, such as may be readily laid between the brick forming the inner wall. Such a flat anchor is provided with a hook end which hooks about the central portion of the anchor C.

In construction the anchor C is formed of a

rod of material and is substantially U-shaped having outwardly extending flanges projecting from the free ends of the U. The bracket C comprises a central portion 37 which forms the closed end of the U, and a pair of sides 34 which are in opposed relationship on opposite ends of the central portion 37. Outwardly extending flanges 40 are bent outwardly from the ends of the sides 39 to form a more secure anchor and to better embed the anchor C.

Between the sides 39 of the anchor C, I provide a pocket 41 which is provided with a pair of opposed inwardly sloping side walls 42 and a curved or arcuated base wall 43. This pocket provides a recess behind the center portion 37 of the anchor. Each of the lugs 44 includes a flat surface 45 designed to engage against a surface of the mold, include opposed sides corresponding to the sides 42 of the pocket or recess formed, and include an arcuate surface 46 which forms the arcuated base surface 43 of the pocket 41. The lugs 41 abut along the abutting edges 47 and notches 49 engage about the central portion 37 of the anchor C. These notches 49 are so shaped as to permit removal of the lugs 44, these lugs being shown in dotted outline in Figure 7 of the drawing in partially removed position.

In accordance with the patent statutes, I have

described the principles of construction and operation of my slab anchor and means of embedding the same, and while I have endeavored to set forth the best embodiment thereof, I desire to have it understood that this is only illustrative of a means of carrying out my invention and that obvious changes may be made within the scope of the following claims without departing from the spirit of my invention.

10 I claim:

1. A mold device for attaching a substantially U-shaped anchor to a concrete slab, comprising a pair of abutting lugs designed to overlie the central portion of the U-shaped anchor, and means for attaching said lugs to a mold surface in abutting relation, said lugs holding said anchor with the central portion thereof flush with a surface of the mold during the pouring process.

2. An apparatus for holding a substantially U-shaped anchor in a mold, said apparatus comprising a pair of abutting lugs designed to overlie the central portion of said anchor and to hold said central portion against a surface of a mold, and slots in said lugs designed to receive attaching means for attaching said lugs to said mold during the pouring process.

GEORGE J. SAFFERT.
